UNITED STATES PATENT OFFICE.

ALBERT VOIGT, OF NEW YORK, N. Y.

SEPARATOR AND TRACK FOR SLIDING DOORS.

1,136,631.

Specification of Letters Patent. Patented Apr. 20, 1915

Application filed May 13, 1914. Serial No. 838,202.

To all whom it may concern:

Be it known that I, ALBERT VOIGT, a citizen of the United States, residing in the borough of Brooklyn, in the county of Kings, city and State of New York, have invented a new and useful Separator and Track for Sliding Doors, of which the following is a specification.

This invention relates to the mounting of sliding doors, such as sliding doors for show or wall cases and the like, and relates particularly to a combined runway and separator for the doors, and it is the object of the invention to provide a runway and separator for the doors which is formed of a single piece of material, and which is simple and cheap in construction, neat in appearance and durable.

In the drawing accompanying and forming a part of this specification, Figure 1 is a cross sectional view of a portion of a show case and its doors with my invention applied thereto. Fig. 2 is a perspective view of a pair of doors in section and showing the preferred form of improved runway and separator in relation thereto; and Fig. 3 is a view similar to Figs. 1 and 2 of the preferred form of the combined door runway and separator.

Similar characters of reference designate like parts throughout the different views of the drawing.

As already stated it is the object of the present invention to provide a combined runway and separator for doors which are slideable relative to each other, and in the embodiment of the invention illustrated in the drawing I have shown the same in connection with a pair of doors 6, 7 of a show or wall case or the like, the top and bottom edges of said doors engaging in longitudinal grooves in the top 8 and base 9 of the case.

In the usual construction of show cases and the like the lower edges of the doors engage directly in the groove in the base, or are supported upon rollers engaging in such groove, as shown at 10 in Figs. 1 and 2, and in order to maintain the doors in proper spaced relation a rail, usually of wood, is fixed in said groove to extend be-

tween the doors. Furthermore, the doors or the door-supporting rollers slide or run upon the bottom of the groove with the result that it soon becomes worn interfering with the easy operation of the doors.

It is the object of the present invention to overcome the above disadvantages and for this purpose I provide a runway and separator for the doors bent up or formed of a single piece of metal to a shape substantially T shaped in cross section. The preferred form of the runway is as shown in Figs. 2 and 3 in which the sheet is bent at right angles to provide a central or body portion 11 and a portion 14 which latter portion is bent reversely upon itself, as at 13, and then again bent upon itself, as at 12, toward the central portion 11 so as to lie contiguous thereto thereby forming a central portion 70 having laterally and oppositely extending portions or flanges along one longitudinal edge, the flange portions 12, 14 extending substantially the same distance from the central portion 11. The flanges have countersunk openings for fastening means, such as screws, to secure it in the case groove so that the flanges 12, 14 will form a lining for the bottom of the lower groove upon which the doors or door-supporting rollers engage, 80 and forming the top of the groove in the top of the case, the central portion 11 engaging between the doors, as clearly shown in Figs. 1 and 2. By this construction it will be obvious that the runway upon which 85 the doors or door-supporting rollers are supported consists of a double thickness of metal which will not be readily worn by the to and fro movement of the doors or door-carrying rollers.

To maintain the doors in a fixed spaced relation to each other the central body portion 11 may be provided with oppositely bulbed portions to extend longitudinally thereof, shown at 16, Fig. 1.

Having thus described my invention, I claim:

In show cases and the like the combination with a pair of doors slideable relative to each other and a runway in which said doors engage, of a separator to extend between the doors and having opposite right

angle portions to engage with the bottom of the runway, comprising a sheet of metal bent substantially at right angles and then one of said right angle portions bent ⁵versely upon itself to project beyond the other portion of the right angle and then again bent upon itself toward said latter

portion of the right angle to lie contiguous thereto to form a structure substantially T-shaped in cross section.

ALBERT VOIGT.
